UNITED STATES PATENT OFFICE

EMIL SCHIMANEK, OF BUDAPEST, HUNGARY, ASSIGNOR TO THE FIRM HERMES MAG-YAR ALTALANOS VALTOUZLET RESZVENYTARSASAG, OF BUDAPEST, HUNGARY

CARBURETOR

Application filed March 16, 1927, Serial No. 175,872, and in Hungary September 11, 1926.

This invention relates to a carburetor in which the whole amount of air drawn through the carburetor is utilized for primary and secondary mixing purposes, and a member is provided for regulating the secondary mixture and controlled by the negative pressure at the secondary mixing point (which member has an internal passage for conveying the primary mixture to said secondary mixing point); said member maintaining the negative pressure constant at the said point, irrespective of the variations in the number of revolutions of the engine fed by the carburetor.

It is essential that such automatically regulating carburetors must comply with two opposed conditions: first, having regard to good volumetric efficiency of the engine, the negative pressure maintained constant at the point of secondary mixing by the automatic regulating member must be as small as possible, for the reason that if the said pressure is very pronounced at this point, the maximum quantity of the charge drawn into the engine cylinder is reduced; and, second, the more pronounced the negative pressure, the more thorough the atomization.

The present invention renders it possible to fulfill both conditions completely; and it consists essentially in disposing between the fuel inlet controlled by the regulating member, and the outlet opening of the fuel passage provided in said member, an atomizing tube which widens towards the outlet of said passage and is provided with air inlet openings.

In this way, the drop in pressure taking place between the suction opening and the outlet opening for the secondary mixture can be divided into two stages. One of these stages, namely that which acts on the mixture-regulating member and controls the secondary mixture, can be sufficiently small to affect as little as possible the maximum charge of the engine, while the other, namely the amount of negative pressure at the atomizing point in the atomizing tube can be substantially greater, in order that the atomizing may yield, together with the secondary mixing, as perfect a total effect as possible.

Several constructions according to the invention are diagrammatically illustrated in longitudinal section, by way of example, in the accompanying drawings.

Figure 1 shows a carburetor in which the atomizing tube is situated in the rod of the floating regulating piston;

Fig. 2 shows a slightly modified arrangement in which the atomizing tube is submerged in the float chamber, this being the preferred form;

Fig. 3 is a modification of Fig. 2, having means for effecting double atomizing;

Fig. 4 is another modification, showing the automatic regulation of the atomizing air;

Fig. 5 is still another modification, providing for hand regulation of the composition of the secondary mixture and of the quantity of air used for atomizing;

Figs. 6 and 7 show developments of the valve for regulating the air supply for both the secondary and the primary mixtures; and

Fig. 8 shows a carburetor in which the load of the regulating piston acts in two stages.

In Fig. 1, 1 indicates the inlet opening through which the air passes into the carburetor, and 2 the outlet opening for the secondary mixture which is in communication with the induction pipe of the engine, said pipe having a throttle valve (not shown). 3 is a floating piston which constitutes the regulating member and which is vertically movable in the cylinder 4.

5 is an opening in the cylinder wall which is uncovered as the piston 3 rises, and 6 is the float chamber containing the fuel, maintained at a constant level by the float 77 by means of the valve 8. The piston 3 is equipped with a hollow rod 9 that extends downward from it into the float chamber, and into the lower end of this rod projects a tapered needle 10 which closes the fuel inlet 11 in accordance with the position of the piston. At the point 14 where the mixture of fuel and air (produced as hereinafter described) passes through the opening 5 into the mixing chamber 16, said mixture is mixed with the air entering said chamber in the direction of the arrow 15 and forms a secondary mixture, the first mixture being the primary one.

The negative pressure prevailing at the point 14 is transmitted through an opening 17 formed in a partition provided in the piston to the space above the piston, so that the said pressure effects the regulation by moving the piston when, for instance, owing to the increased number of revolutions of the engine, the negative pressure is intensified, that is to say, overcomes the weight of the piston and the action of its spring, if any.

According to the invention, and in order that the negative pressure acting on the piston shall be as small as possible, while pronounced negative pressure is available for atomizing purposes, a Venturi tube 12 is connected to the floating piston 3 and surrounds the upper portion of the rod 9. This tube widens toward the point 14, where it opens into chamber 16, and it is provided at its lower end with an air inlet 13 which opens into the suction chamber of the carburetor. Pronounced negative pressure prevails in the narrower lower portion of said Venturi tube, owing to which the fuel is atomized in an effective manner, and a rich primary mixture is produced, the pressure of which is gradually increased in the widening portion of the tube towards the point or opening 14. On reaching this opening, the negative pressure is small, but sufficient for thoroughly mixing the well-atomized primary mixture with the abundant air supply at the opening 14.

The bore 13^b of the upper portion of the piston rod 9 leads from the space above the piston 3 down to the point 13^c where atomization takes place. The space above the piston 3 is in communication, through the opening 17, with the opening 14 which is under a considerably higher negative pressure than that prevailing at point 13^c. Consequently, a portion of the primary mixture flows through the opening 17, the bore 13^b of the rod 9 and a small opening or openings 34 at the bottom of said bore, in the direction of the arrow 13^b back to the atomizing point 13^c, owing to which the atomizing is assisted.

According to Fig. 2, the lower end of the Venturi tube 12 extending from the floating piston 3 projects below the level of the liquid in the fuel chamber 6 into a cup 18 which opens above the said level and which is mounted on the lower end of the rod 9 disposed in the interior of the Venturi tube 12. The lower portion of the rod 9 has a bore 32 which is separated from the bore 13^b of the upper portion by a partition 31 and into which projects the needle 10 that controls the cross-sectional area of the fuel inlet 11; said bore 32 communicating with the atomizing tube 12 by means of one or more openings 30 situated below the level of the liquid. The bore 13^b communicates through the opening or openings 34 just above partition 31 with the passage provided by the interior of the atomizing tube 12, so that a portion of the

primary mixture returns in the direction of arrow 13^a, as before.

In this construction, it is not necessary, therefore, to raise the fuel to the atomizing point 13^c, so that the whole of the negative pressure is thus utilized for atomizing. This arrangement has the further advantage that while the engine is at rest the fuel collects in the cup or chamber 18 until it reaches the level of the liquid in the float chamber, owing to which a richer mixture is available for starting.

The arrangement shown in Fig. 3 is similar to that shown in Fig. 2, with the exception that a double atomizing operation occurs instead of a single one, the first one taking place at 19, and the second at 20. The mixture return 13^b shown in Figs. 1 and 2 is omitted here.

In the construction shown in Fig. 4, the quantity of air used for the primary mixture is varied simultaneously with the quantity of air producing the secondary mixture. To this end, the air inlet 13 of the atomizing tube 12 is situated between the part 35 of that tube which is secured to the piston 3, and the fuel-supply tube 28 which is secured to the carburetor casing. The needle 10 controlling the cross-sectional area of the fuel inlet 11 is also mounted on the piston 3. Consequently, the vertical movement of the piston likewise alters the width of the air inlet 13.

Fig. 5 shows an arrangement in which, by rotating the piston 3 about its axis, the free cross-section of the opening 5 controlled by the piston can be altered, while the level of the piston 3 remains invariable, owing to the provision of a depending skirt 21 on the piston which acts as a slide valve to close the opening 5 to a greater or lesser extent. The edge 7 of the skirt 21 (Fig. 6) moves to the position 7¹, more or less to the left of the edge 7 of the opening 5, the opening 14 remaining in any position 14-14¹ within reach of the opening 5. In this way, while the open cross-sectional area of the fuel inlet 11 remains invariable, the cross-section afforded to the air passing through the opening 5, and consequently the composition of the secondary mixture produced at a given level of the piston 3, can be altered.

In such a construction, it may be desirable to vary also the quantity of air utilized for atomization; and to this end, the carburetor shown in Fig. 5 has a device for altering the said quantity of air when the double atomizing feature of Fig. 3 is utilized. The lower portion 19 of the atomizer 12 projects into and is attached to cup 18, and the latter is mounted in a cylinder 23 secured to the carburetor casing, so that the atomizer and cup are thus vertically adjustable and rotatable as a unit; said cylinder 23 being provided with an aperture 24 (Fig. 7) for cooperation with a pair of air inlet openings 22, 22¹.

formed in the cup and communicating with the interior of the atomizing tube. Hence, the rotation of the piston 3 and the atomizing tube 12 secured to the same, will bring a more or less greater portion of the air inlet openings 22, 22^a of said tube into register with the aperture 24 of the cylinder 23, resulting, in consequence, in a greater or a smaller quantity of air passing into the atomizer.

10 In the device shown in Fig. 8, the floating regulating piston is provided (with a certain amount of play) with a resisting spring 26, so that, on starting, the engine suction first overcomes the weight of the piston only, and 15 then the spring resistance. According to Fig. 8, the resisting spring 26 acts on the rod 25 secured to the piston and containing the fuel passage and arranged in the interior of the atomizing tube, so that the inlet 13 for 20 the atomizing air is between this rod and the wall of said tube. Consequently, the air inlet 13 is narrow in the lowest position of the piston, i. e., when starting. For this reason, the negative pressure acting on the fuel in the 25 passage is relatively high, so that the carburetor supplies at the start a rich mixture even if suction is weak, owing to the small number of revolutions of the engine. The piston rises, even when negative pressure is 30 small, until it reaches the stop 27 on the upper end of rod 25, at which moment, the inlet 13 has reached its normal width, and the spring 26 becomes operative, so that the regulating piston rises further only when 35 negative pressure increases still more.

Having now particularly described and ascertained the nature of my said invention and in what manner the same is to be performed, I declare that what I claim is:

- 40 1. In a carburetor; a fuel chamber, a floating piston thereabove; a cup supported by the piston for movement therewith and having its lower portion submerged in the fuel in said chamber and its upper portion opening above the level of the fuel; an atomizing tube rigidly connected to the bottom of the piston and projecting at its lower end into said cup below the level of the fuel and provided at the latter end with an air inlet; and 45 a fuel inlet at the bottom of said cup and extending into said tube, said inlet being controlled by the movements of the piston.
2. In a carburetor, a fuel chamber; a floating piston thereabove; a cup supported by 50 the piston for movement therewith and having its lower portion submerged in the fuel in said chamber and its upper portion opening above the level of the fuel; an atomizing tube rigidly connected to the bottom of the piston and projecting at its lower end into said cup below the level of the fuel and provided at the latter end with an air inlet; fuel supply means at the bottom of the cup 55 extending into said tube; and a needle valve secured to the bottom of the fuel chamber

and projecting upwardly into said tube to control the passage of fuel therethrough.

3. In a carburetor, a casing having an air inlet at its lower portion and a mixture outlet at its upper portion; a floating piston in the casing for directly controlling the outlet; an atomizing tube rigidly connected to the piston and providing an internal mixture passage which opens at its upper end through the side wall of the piston for communication with said outlet and has an air inlet at its lower end, said passage also having an opening in its top wall for transmitting engine suction to a point above the piston so as to control the position of the latter exclusively by such transmitted suction.

4. In a carburetor, a fuel chamber; a cylindrical casing on said chamber and provided at its lower portion with an air inlet and at its upper portion with an outlet for the carbureted mixture; a floating piston in said casing for directly controlling said outlet; a tube rigidly secured to said piston and providing an internal passage for conveying a mixture of fuel and air to the outlet, said tube having an air inlet at its lower end; a cup supported by the piston and having its lower portion submerged in the fuel in said chamber and its upper portion opening above the fuel level, said tube having its lower end projecting into the cup below the fuel level; and means controlled by the movements of the piston for supplying fuel in regulated quantity to the cup and the lower end of the tube to undergo atomization in said tube by the air entering thereinto through the air inlet of the tube.

In testimony whereof I affix my signature.
EMIL SCHIMANEK.
